ENOCH THOMAS, OF CRAIGSVILLE, VIRGINIA.

Letters Patent No. 90,970, dated June 8, 1869.

IMPROVED HAY AND COTTON-PRESS.

The Schedule referred to in these Letters Patent and making part of the same.

To all whom it may concern:

Be it known that I, ENOCH THOMAS, of Craigsville, in the county of Augusta, and State of Virginia, have invented a new and useful Improved Portable Double-Acting Toggle-Lever Press for Hay, Cotton, &c.; and I do hereby declare that the following is a full and exact description thereof, reference being had to the accompanying drawings, and to the letters of reference marked thereon.

The nature of my invention, mainly, consists, in the first place, in the combination of a vertical-sliding ratchet-bar at each corner of the press-box or case which contains the material to be pressed, with horizontal lifting-bars, upon which the follower rests, the lower ends of the ratchet-bars being jointed to the ends of the lifting-bars, so that a rocking motion may be given to the follower, as its ends are lifted alternately in the pressing-operation, caused by the alternate action of two sets of levers, one set being at each end, or at parallel sides of the press.

In the second place, it consists in the combination of double-acting toggle-levers with the said vertical ratchet-bars, the said levers being operated by means of eccentrics on a driving-shaft, and connecting-rods, or other suitable mechanism.

In the third place, it consists in the combination and arrangement of removable shafts with the press, in such a manner, that when the latter is turned down to a horizontal position, and rests on fly-wheels, on the ends of the driving-shaft, which then serve as traction-wheels, a horse may be placed in the shafts, and the press removed from place to place, as may be desired. And when the press has to be put into operation, the shafts may be detached therefrom.

In the accompanying drawings, which make a part of this specification—

Figure 1 is a side elevation of the improved press.

Figure 2 is an end view of the same.

Figure 3 is a perspective view of one of the vertical ratchet-bars D.

Figure 4 is a like view of one of the horizontal lifting-bars C.

Figures 5 and 6 are views at right angles with each other of one of the vertical slides N.

Figures 7 and 8 are like views of one of the shafts S.

Figures 9 and 10 are views at right angles with each other of a swinging pawl, b'.

Like letters in all the figures indicate the same parts.

A is a box, or case, into which the material to be pressed is put. The top, which may be connected in the usual manner, is not represented.

B is a vertically-sliding bottom, or follower, which rests on horizontal bars, C C, which are jointed to the lower ends of the vertical ratchet sliding bars D at each corner of the case A.

The ratchet-bars, one of which is shown in detail in fig. 3, have tongues, a a, which slide in corresponding

vertical grooves in the case A, represented in figs. 1 and 2.

One of the lifting-bars C is shown in detail in fig. 4.

Instead of the ratchet-bars being jointed to the lifting-bars, they may have a like connection with the follower B. When so connected, the bars C are dispensed with.

The follower B receives its upward movement, whereby the material to be pressed is condensed between it and the top plate, by means of the toggle-levers E and E', at each corner of the pressing-box. The pawls b, on the upper ends of the levers E', in each straightening motion of the pairs of levers, by connecting with the ratchet-bars D, lift the same, so as to elevate the follower B, which rests upon the horizontal bars C, which have a joint-connection with said bars D, as before described.

At one end of the press there is a horizontal rod, F, which has a joint-connection with the two pairs of levers E and E' at that end of the press. The ends of the rod also have a connection with one end of the bars G G, at the sides of the press.

At the other end of the press there is a like rod, F', connected with the two pairs of levers E' E' at that end, and with the other ends of the bars G G, in the same manner.

Alternate action of the levers is produced by means of the eccentrics H H, on the driving-shaft I, and connecting-rods J J, the latter being connected to the coupling-bars G G, which have a reciprocating motion given them by the revolutions of the driving-shaft through said intermediates. By the alternate action of the two sets of levers upon the follower, its edge, at one end of the press, is raised, while the opposite edge is at rest, and *vice versa*, whereby an increased leverage is obtained.

K is a crank, at one end of the press, which is connected to the rods J J by means of the rods L L, for elevating the former rods when it is desired to arrest the motion of the follower.

The pawls b may be instantly thrown out of their connection with the vertical ratchet-bars D by means of the cranks M, at each end of the press, as represented in figs. 1 and 2, the cranks being in connection with the vertical slides N, one at each corner of the case A, and the said slides having inclines, e, at their upper ends, which, during the elevation of the slides, by pressing against the friction-wheels O, on the edge of the levers E, throw their upper end outward.

At one end of the crank M there is a lever, P, for operating the same.

There is a catch, Q, at each corner of the case A, which connects with the ratchet-bar D, which is sprung inward by means of the upper end of the spring R, the lower end of which acts upon the upper end of the lever E, to throw the pawl b into connection with the said bar.

Figs. 7 and 8 represent a draught-shaft, which has holes, *f f*, for the admission of screw-bolts. And there are like holes, *f'*, in the horizontal timbers *S' S''* at the bottom and near the top of the case *A*, as seen in fig. 2.

When I wish to remove the press, I bolt a pair of these shafts to the said timbers *S' S''*, and turn the case *A* into a horizontal position, so as to cause it to rest with its weight on the fly-wheels *T T*, on the ends of the driving-shaft *I*, and hitching a horse in the shafts, the press may be readily removed from place to place, when desired.

I do not claim the combination of double-acting toggle-levers with pawls at their upper ends for elevating the follower of the press, as such an arrangement ex-

ists in my patent dated the 14th day of July, 1868; but

I claim the ratchet-bars *D*, in combination with the double-acting toggle-levers *E E'*, when operated by the coupling-bars *G*, connecting-rods *J*, eccentrics *H*, and driving-shaft *I*, all constructed and arranged in the manner herein set forth.

In testimony that the above is my invention, I have hereunto set my hand and affixed my seal, this 4th day of March, 1869.

ENOCH THOMAS. [L. S.]
